UNITED STATES PATENT OFFICE.

FELICE MASSA, OF CRANFORD, NEW JERSEY.

FOLDING APPARATUS.

Application filed May 21, 1928. Serial No. 279,270.

This invention relates to the folding and stacking of papers, and more particularly concerns a machine for automatically and continuously removing successive layers or piles of cut paper from a printing and cutting mechanism, folding and stacking said layers and delivering the completed and folded stacks from the machine.

In the printing industry, and more particularly, in the preparation of newspapers, pamphlets, books and other folded printed matter, the successive pages of reading matter are usually printed on a plurality of continuous sheets of paper, these continuous sheets being subsequently delivered in stacked relation to a suitable cutting mechanism which severs the successive double page stacks from each. The number of sheets of paper which can be simultaneously cut in this manner is obviously rather limited, as stacked paper presents considerable resistance to a cutting blade or knife. Thus, only a limited number of paper sheets may be simultaneously cut and delivered from the known types of mechanism, and in the preparation of large editions, such as daily or Sunday newspapers in large cities, the largest stack of sheets which can be cut in a single operation is insufficient to form the entire paper, or even the larger sections thereof. It is, therefore, necessary to manually combine or stack and fold the piles of sheets cut in each successive cutting operation, thereby adding materially to the expense of preparing the paper, and producing a finished paper composed of a plurality of separately folded sections, which are likely to become separated or disarranged before reaching the news dealer or customer.

With the above and other considerations in mind, it is proposed in accordance with the present invention, to provide a mechanism for automatically stacking any desired number of successively cut piles of double page sheets, and successively delivering the completed newspapers or other completed volumes of reading material in single folded sections, from the mechanism.

The invention further contemplates the provision of means for creasing each pile of paper sheets as it is being cut, whereby the successive piles may be readily nested together in aligned relation by other parts of the mechanism. Novel means are provided for maintaining the successive piles of cut sheets in proper alignment while

other piles are being cut and stacked thereon, thereby preventing the folding, tearing or crumbling of the sheets during the stacking operation. The mechanism of the invention includes means for delivering the completed paper in a single folded section after the desired number of sheets have been stacked, this means being adjustable to deliver a complete paper of any desired number of pages.

Various other objects, advantages and characteristic features of the invention will become apparent as the description thereof progresses.

In describing the invention in detail, reference will be made to the accompanying drawings, in which:

Figure 1 is a side view, partly in section, representing in a diagrammatic and simplified manner, the machine embodying the present invention.

Fig. 2 is a sectional end view of the machine, taken along the line 2-2 of Fig. 1; and

Fig. 3 is a plan view of the stacking mechanism with the cutting mechanism removed.

The machine of the present invention comprises in general a cutting cylinder C, a co-operating paper carrying cylinder D, adjacent and parallel to the cutting cylinder, and a plurality of automatically operated devices on the cylinder D and below this cylinder for removing the sheets of paper and arranging them in stacked or nested relation in a single section.

The machine includes a pair of parallel side frames 1 of any suitable construction, in which the shafts 2 and 3 of the cylinders C and D are suitably journaled in parallel and horizontally aligned relation. The shafts 2 and 3, together with the cylinders C and D are fixed thereto, are continuously driven in opposite directions and at the same peripheral speed by a suitable source of power applied, for example, to the pulley 4 on the shaft 3, the power being transmitted to the shaft 2 by suitable gearing such as the gears 55, 56, 57 and 58. A plurality of radially disposed cutting blades or knives 5 are fixed to the surface of the cylinder C, and in the present embodiment, two such blades are provided at diametrically opposite points on this cylinder. The cylinder D is provided with recesses at points on the peripheral surface thereof corresponding to

the points at which the cutting blades 5 are located on the cylinder C. These recesses are preferably filled with soft rubber blocks 6, and the knives 5 press into the recesses and cut the paper sheets by compressing these rubber blocks.

The paper carrying cylinder D is provided with a plurality of paper engaging pins 7, arranged in rows across the cylindrical surface thereof at diametrically opposite points, as shown in Fig. 1. The pins are mounted at an angle to the radius of the cylinder D as shown, and are movable to and from positions in which they project 10 from the surface of the cylinder, to successfully engage and release the papers carried on the surface thereof. As pins of this type and the operating mechanism therefor are well known in the art, and form no part 15 of the present invention, the operating mechanism therefor has not been shown in the drawings. It is sufficient for the purpose of disclosing the present invention to understand that suitable means are provided 20 for maintaining each row of pins 7 in the extended, paper engaging position and for withdrawing each row of pins from the paper during a brief interval of cylinder travel as the pins approach and pass the 25 point W substantially diametrically opposite to the point at which each cutting blade 5 engages its corresponding rubber block 6.

Referring now more particularly to the paper creasing and discharging mechanism 30 on the cylinder D, which comprises one of the important features of the present invention, two diametrically opposite radially disposed push plates 8 are slidably carried in suitable recesses in the walls of the cylinder D as clearly shown in Figs. 1 and 2. Each of the plates 8 is carried by a pair of rods 9, the inner ends of which are engaged by suitable rollers carried on the ends of the levers 10 fixed to the shaft 11 which is suitably 40 journaled within the cylinder structure. The inner or retracted positions of the plates 8 are limited by the stops 12 which are engaged by the levers 10, and suitable spring means such as the coil springs 13 surrounding 45 the rods 9 and fixed to the inner ends thereof are employed to normally retain the plates 8, together with the levers 10, in their retracted positions. In their fully retracted positions, the outer edges of the plates 8 are flush with the surface of the cylinder D, but these outer edges are provided with outwardly extending ridges or tongues 14 which protrude radially from the surface of the cylinder D when the plates are fully 50 retracted. The cutting cylinder C is provided with two diametrically opposite grooves 15 across its cylindrical surface for the reception of the tongues 14 during the rotation of the cylinders. Each of the operating shafts 60 11 for the push plates 8 is provided with a

suitable cam 16, fixed thereto at a point beyond the end of the cylinder D as shown in Fig. 2. Each cam 16 is arranged to engage a fixed stop 17 adjacent the end of the cylinder, this stop being arranged to quickly 70 raise the cam, turn the shaft 11 and project the corresponding push plate 8 from the surface of the cylinder D. The stop 17 is so disposed and shaped that each plate 8 is rapidly projected from the surface of the 75 cylinder as this plate passes its lowermost position, as shown in Fig. 1, the plate being immediately retracted within the cylinder D as its lowermost position is passed.

Two sets of arcuate guide strips 18 and 19 are suitably supported in spaced relation to the surface of the cylinder D, extending from points adjacent a horizontal plane through the axis of this cylinder, to points substantially half-way to the lowermost 85 point thereof, as shown in Fig. 1. A plurality of straight guide strips 20 and 21 are respectively hinged to the lower ends of the two sets of arcuate guide strips 18 and 19, the strips 20 and 21 normally lying in converging relation to form a V-shape trough or folding compartment T, as shown in Fig. 1. The lower ends of the guide strips 20 and 21 are at times held in engagement, and at times 90 separate, by means of a suitable linkage arrangement, which is most clearly shown in Figs. 1 and 2. Each strip comprising the set 20 is pivotally connected by a bar 22 to the lower end of a lever 23, each lever 23 being fixed to the shaft 24. One of the levers 23 is pivotally connected through a bar or rod 25 to a lever 26 fixed to a second shaft 27 on the opposite side of the folding trough T, and each strip of the set 21 is pivotally connected through a bar 28 to a lever arm 29 fixed to the shaft 27. It will be readily apparent that when the shaft 24 is turned in a clockwise direction as viewed in Fig. 1, the linkage described acts to separate the lower 100 ends of the two sets of straight guide strips 20 and 21, thus opening the lower end of the trough T.

A cam follower lever 30 is fixed to the shaft 24, and a suitable roller 31 on the free end of this lever is engaged by a cam 32. Suitable means such as a spring 33 is employed to normally maintain the guides 20 and 21 in the closed position as shown, and to press the cam follower roller 31 into engagement with the cam 32. The cam 32 is 115 rotated in timed relation with the cylinders C and D by suitable means as hereinafter described.

Two parallel sets of rollers 33 and 34 are fixed respectively to the parallel shafts 35 and 36 located adjacent and on either side of the end of the trough T. As shown in Fig. 2, these rollers are arranged to lie between the adjacent strips of the sets 20 and 21 so that these strips may be separated 125 130

without coming into contact with the rollers. The shaft 36 carrying the rollers 34 is journaled in a pair of movable arms 37 which are pivotally secured to the shaft 38. A rod 5 or rods 39, pivotally secured to one or both of the arms 37, and connected through springs 40 to the lever 23, enables the rollers 34 to be drawn away from the rollers 33 when the linkage operates to open the trough 10 T, as will be clear from the disclosure of Fig. 1.

Disposed directly below and parallel to the shafts 35 and 36 are two shafts 41 and 42, respectively carrying two interengaging rolls 43 and 44. The shaft 42 is journaled in two pivotally mounted levers 45, the lower ends of which are biased by the springs 46 in such a manner that the roll 44 is resiliently pressed against the roll 43. The inter- 20 engaging rolls 43 and 44 are respectively driven in opposite directions by two gears 47 and 48, mounted respectively on the shafts 49 and 38 and respectively engaging the gears 50 and 51 on the roll shafts 41 and 25 42. The gear 47 is driven by a suitable source of power through a gear 52, the driving power being transmitted to the roll 43 through the gear 50 and to the roll 44 through gears 48 and 51 thus rotating the 30 rolls 43 and 44 in opposite directions as indicated by the arrows. The gears 47 and 48 further respectively engage two gears 53 and 54 on the shafts 35 and 36, thus turning the sets of rollers 33 and 34 in opposite directions as indicated by the arrows.

Referring now to the means for withdrawing the papers from the cylinder D and retaining these papers in order until an edition has been completed, two shafts 59 and 60 are suitably journaled in the side frames 40 1 in positions parallel to the cylinder shafts 2 and 3. The shaft 60 is driven from the shaft 3 through suitable gears 61 and 62, the gear ratio being so chosen that the shaft 60 45 is driven at twice the angular velocity of the shaft 3. The shaft 59 is driven at the same speed as the shaft 60 through two shafts 63 and 64, which are respectively geared to the opposite ends of the shafts 59 and 60 through 50 the bevel gears 65 and 66, as most clearly shown in Fig. 3. Fixed respectively to the mid-points of the shafts 63 and 64 are two radially extending blades or arms 67 and 68. The shafts 63 and 64 rotate in opposite 55 directions as indicated by the arrows in Fig. 3, and the arms 67 and 68 are so disposed on the shafts as to occupy corresponding positions during the operation of the machine, the inner ends thereof moving inwardly and 60 downwardly in horizontally aligned relation, as shown in Fig. 2. The rotation of the shafts 63 and 64 is so timed with respect to the rotation of the drum D that the ends of the arms 67 and 68 move inwardly and 65 downwardly adjacent the ends of each push

plate 8, as such plate is projected radially on the cylinder D.

Two pairs of retaining fingers 85 and 86 are provided to hold the papers in position while they are being stacked or nested. Each 70 of these fingers normally extends over one upper corner of the trough T in parallel and spaced relation to the sets of guide strips 20 and 21 and suitable mechanism is provided for periodically and simultaneously 75 withdrawing all of these fingers from their normal positions to permit a stack of paper sheets to drop into the trough T. The pairs of fingers 85 and 86 are respectively mounted on pairs of brackets 69 and 70. The brackets 80 69 are slidably mounted on the shaft 60 and a parallel shaft 71, and are pressed together by a pair of coiled spring 72 on the shaft 71 as shown in Fig. 3. Similarly, the brackets 70 are slidably mounted on the shaft 59 and 85 a parallel shaft 73, and are pressed together by a pair of coiled springs 74 surrounding the shaft 73. The adjacent faces of the pairs of brackets 69 and 70 are respectively provided with pairs of aligned horizontally 90 journaled rollers 75 and 76. Two double-faced cams 77 and 78 are respectively fixed to the mid-points of the shafts 60 and 59, being arranged to respectively engage the pairs of rollers 75 and 76, as clearly shown in 95 Figs. 1 and 3. The surfaces of the cams 77 and 78 are designed to simultaneously separate the pairs of brackets 69 and 70 respectively during a certain portion of each rotation of these cams. The cam driving 100 means is so timed that the pairs of brackets 69 and 70 are separated and the pairs of fingers 85 and 86 thus withdrawn from the trough T at the points in the operation of the mechanism at which the push plates 8 are 105 extended from the cylinder D.

The cam 32 which operates the folding trough linkage is fixed to a suitable shaft 79 which is driven through a gear train 80—81 from the shaft 60 (see Fig. 1). As 110 explained above, the shaft 60 rotates at twice the angular velocity of the cylinder shaft 3, and the gears 80 and 81 between the shaft 60 and the cam shaft 79 are preferably arranged to drive the cam shaft at one-half 115 the angular velocity of the cylinder shaft 3, that is, one-quarter the angular velocity of the shaft 60. When thus arranged, the cam 32 moves the linkage to open the trough T once during each two complete revolutions 120 of the paper cylinder D. The gear train between the shaft 60 and the cam shaft 79 may be altered to turn the cam 32 at any desired angular velocity relative to the angular velocity of the cylinder D. Thus, the cam 32 125 may be arranged to open the trough T twice during each revolution of the cylinder D, once during each revolution thereof, or in any other fixed relation desired. The gear train 80—81 is arranged in such a manner 130

that the cam 32 operates the linkage and opens the trough T at a point in the rotation of the cylinder D when neither of the push plates 8 are in their radially extended positions. Thus, the trough T is not opened while papers are being pushed from the surface of the cylinder D.

The operation of the machine embodying the present invention will now be described.

- 10 A plurality of aligned continuous sheets of printed paper 82 are continuously delivered to the machine between cylinders C and D. The number of sheets thus delivered is usually determined by the capacity of the cutting blades 5 and the maximum number of sheets so delivered represents either the maximum number that can be properly cut in a single operation, or the maximum number that can be simultaneously printed. These 15 paper sheets 82 may be folded or may comprise a single unfolded stack, and the number of sheets may be varied in accordance with the printing mechanism employed or the size of the edition required. When the paper 20 folding machine of the present invention is applied to the mechanism for printing newspapers, the continuous sheets 82 preferably comprise the successive pages of a portion or the entire edition of the newspaper, these 25 papers being printed in double page arrangement, so that when severed from each other, stacked together in the open condition and then folded along the center line between the pages, they form a properly arranged completed edition of the desired size. 30
- The descending edge of the continuous paper sheets 82 enters the space between the cylinders C and D and is impaled upon the pins 7 carried by the cylinder D. These 35 pins carry the sheets around on the cylindrical surface of the cylinder D and when the cylinders have turned through approximately one-quarter of a revolution, the tongue 14 on the push plate 8 of the cylinder D enters the corresponding groove 15 in the cutting cylinder C, thereby forming a crease along the center line between the double 40 pages of the papers 82. The rotation of the cylinders continues, and when the cylinder D has completed one-half of a revolution, the cutting blade or knife 5 on the cylinder C presses against the papers 82 and cuts off a stack of double page sheets 83. 45

50 At this point in the operation of the machine, the pins 7 at the point W are withdrawn within the cylinder D and thus retracted from the edge of the stack of papers, and the lowermost push plate 8 is depressed or extended to the position shown in Fig. 55 1, thus carrying the severed stack of papers 83 away from the surface of the cylinder D and into the top of the trough T. As the stack of papers 83 is thus spaced from the cylinder D, the arms 67 and 68 enter 60 the opposite ends of the stack 83, engaging the

the upper surface thereof at the crease 84 and pressing the stack downwardly into the trough T to the position shown at 87 in Fig. 1. Just as the stack 83 is thus pushed away from the cylinder D, the cams 77 and 78 separate the pairs of brackets 69 and 70, thus withdrawing the fingers 85 and 86 from the trough T to the positions shown in full lines in Fig. 3.

65 After the stack 83 has been pushed to the bottom of the trough T by the arms 67 and 68, the cams 77 and 78 release the brackets 69 and 70. The springs 72 and 74 then press the brackets 69 and 70 together, thus carrying the retaining fingers 85 and 86 over the edges of the stack to the positions shown in dotted lines in Fig. 3. The retaining fingers 85 and 86 are thus withdrawn as each stack 83 of papers is pushed over the stack after the papers are fully seated in the trough. The fingers 85 and 86 hold the papers in a V-shape position in the trough T, preventing the drifting of the upper sheets across the trough due 90 to air currents, the resiliency of the paper, or other causes. In this manner, the dis- 95 arrangement or crumpling or tearing of papers in one stack by those of the next successive stack is prevented. The above 100 described operation of the cutting and carrying cylinders C and D continues until a sufficient number of stacks of paper 83 have been nested within the trough T to complete an edition of the required size.

105 In the embodiment of the invention disclosed in the drawings, it is assumed that the edition being prepared comprises four stacks 83 of double page sheets. Thus the cam 32 is arranged to open the trough T once during each two complete revolutions of the cylinder D. In each revolution of the cylinder, two stacks of sheets 83 are deposited in the trough T in the manner described above, and immediately after four such stacks have 110 been so arranged, the cam 32 moves the lever 30, turning the shaft 24 in a clockwise direction as viewed in Fig. 1, and opening the lower end of the trough T as described above. This action of the cam 32 115 also moves the set of rollers 34 away from the cooperating rollers 33, and the completed edition of the paper drops between these rollers, is advanced thereby to the inter-engaging rolls 43 and 44, and is thereby 120 rapidly carried out of the lower end of the trough T. As the paper passes between the rolls 43 and 44, the roll 44 moves to the left, as shown in Fig. 1, the spring 46 being compressed and the paper being 125 thereby firmly gripped and positively advanced. Just after the upper edge of the paper has passed through the open lower end of the trough T, the cam 32 releases 130 the lever 30, and the spring 33, acting

through the linkage, closes the trough T. The operation of the cylinders C and D is not interrupted while the paper is being discharged from the trough T, and as soon as the trough has closed, the first stack 83 of double page sheets comprising another paper, is dropped into the trough from the cylinder D. The open positions of the guide strips 20 and 21 of the trough T, and of the rollers 34, 10 as well as the positions assumed by the elements of the linkage connected to these parts, have been indicated by dotted lines in Fig. 1.

When it is desired to increase or decrease the size of the edition or the sections thereof which are to be folded together, the gear ratio between the shafts 60 and 79 is altered. Thus if every stack 83 of double page sheets is to be separately folded and delivered, the cam 32 is driven at the same speed as the shaft 60; that is, at twice the angular velocity of the cylinder D. When driven in this manner, the trough T folds and delivers each stack 83 of papers as soon as such stack is pushed from the cylinder D into the trough T. It is readily apparent that the gear ratio between the shafts 60 and 79 may be varied to adapt the trough mechanism for the making up of editions composed of any desired number of stacks 83.

It should be understood that the size and shape of the cam 32 may be suitably varied if necessary when the gear ratio between the shaft 60 and the cam shaft 79 is changed. 35 The raised portion of the cam 32 is preferably arranged to operate the linkage and successively open and close the trough T rather quickly, as this trough must necessarily be closed whenever a stack of cut 40 papers 83 is delivered thereto.

From the description given, it will be readily apparent that the machine of the present invention is adapted to automatically cut, crease, arrange in nested relation, fold together and deliver any number of stacks of paper, thus combining and delivering a completed edition comprising any desired number of double page sheets in a compact and unitary form. It should be particularly noted that the size of the completed edition is in no way limited by the maximum number of sheets which can be simultaneously printed or cut, as the nesting or stacking operation can be automatically continued until an edition of any desired size has been built up. Further, the mechanism can be employed to fold and deliver small editions as well as large, it being entirely feasible to handle single sheets of paper if desired. The mechanism is simple in construction and inexpensive, and operates continuously without manual attention.

Although the present invention has been 65 described in connection with a single specific

machine, it should be clearly understood that various changes and modifications, as well as omissions, may be made in the construction and arrangement of the elements shown, without departing from the scope of 70 the invention as defined by the appended claims.

I claim:

1. A machine of the character described, in combination with a cylinder on which a plurality of successive stacks of double page sheets are carried, means on said cylinder for successively pushing the mid-portions of said stacks away from said cylinder, a tapered trough adjacent said cylinder, means adjacent said trough for successively engaging said stacks at their mid-points and carrying said stacks into said trough in nested relation, and means for removing said combined stacks of paper from said trough after 85 a predetermined number of said stacks have been received from said cylinder.

2. A machine of the character described, in combination with a cylinder on which a plurality of successive stacks of double page sheets are carried, means on said cylinder for successively pushing the mid-portions of said stacks away from said cylinder, a tapered trough adjacent said cylinder, means adjacent said trough for successively engaging said stacks at their mid-points and carrying said stacks into said trough, means for maintaining said papers in engagement with said trough in nested relation, and means for removing said combined stacks 100 of paper from said trough after a predetermined number of stacks have been received from said cylinder.

3. In a machine of the character described, a rotary paper carrying cylinder, 105 means for carrying a plurality of continuous paper sheets on the surface of said cylinder, means for cutting said sheets into stacks of predetermined length during the rotation of said cylinder, a V-shaped trough 110 communicating with the surface of said cylinder, means for successively transferring said severed stacks of paper sheets from said cylinder to said trough and means for retaining said stacks of paper in V-shaped and partially folded condition and 115 nested relation within said trough.

4. In a machine of the character described, a rotary paper carrying cylinder, 120 means for carrying a plurality of continuous paper sheets on the surface of said cylinder, means for cutting said sheets into stacks of predetermined length during the rotation of said cylinder, a V-shaped trough 125 communicating with the surface of said cylinder, means for successively transferring said severed stacks of paper sheets from said cylinder to said trough, means for retaining said stacks of paper in nested V-shaped relation within said trough, and means for 130

periodically removing a plurality of combined stacks of paper from said trough and folding said stacks in a single section.

5. In a machine of the character described, a rotary paper carrying cylinder, means for carrying a plurality of continuous paper sheets on the surface of said cylinder, means for cutting said sheets into stacks of predetermined length during the rotation of said cylinder, a downwardly tapered paper receiving trough below said cylinder communicating with the surface thereof, means for successively transferring said stacks of papers from said cylinder to said trough in nested relation, and means for periodically opening the lower end of said trough whereby a predetermined number of papers may be withdrawn from said trough and simultaneously folded into a single section.

6. In a machine of the character described, a rotary paper carrying cylinder, means for carrying a plurality of continuous paper sheets on the surface of said cylinder, means for cutting said sheets into stacks of predetermined length during the rotation of said cylinder, a downwardly tapered paper receiving trough below said cylinder communicating with the surface thereof, means for successively transferring said stacks of papers from said cylinder to said trough in nested relation, means for periodically opening the lower end of said trough whereby a plurality of nested stacks of papers may drop therefrom, and means for simultaneously folding said papers in a single section and withdrawing said section from said trough.

7. In a machine of the character described, a rotary paper carrying cylinder, means for carrying a plurality of continuous paper sheets on the surface of said cylinder, means for cutting said sheets into stacks of predetermined length during the rotation of said cylinder, a downwardly extending V-shaped trough adjacent said cylinder and having the upper end thereof in communication with the cylindrical surface of said cylinder, means on said cylinder for successively displacing the mid-points of said paper stacks from the surface of said cylinder, means adjacent the ends of said trough for engaging the mid-points of said paper stacks and successively drawing said stacks from said cylinder into said trough in nested V-shaped relation, and means for periodically removing a plurality of said nested stacks from said trough in a single nested section.

8. In a machine of the character described, a rotary paper carrying cylinder, means for carrying a plurality of continuous paper sheets on the surface of said cylinder, means for cutting said sheets into stacks of predetermined length during the rotation of

said cylinder, a downwardly extending V-shaped trough adjacent said cylinder and having the upper end thereof in communication with the cylindrical surface of said cylinder, means on said cylinder for successively displacing the mid-points of said paper stacks from the surface of said cylinder, means adjacent the ends of said trough for engaging the mid-points of said paper stacks and successively drawing said stacks from said cylinder into said trough in nested V-shaped relation, means for retaining said papers in a V-shaped position in said trough, and means for periodically removing a plurality of said nested stacks from said trough in a single nested section.

9. In a machine of the character described, a rotary paper carrying cylinder, means for carrying a plurality of aligned continuous paper sheets on the surface of said cylinder, means for cutting said sheets into stacks of a predetermined length, means for creasing said stacks at their mid-points, a downwardly tapered trough below said cylinder communicating with the surface thereof, means for successively removing said stacks from said cylinder to said trough with their creased edges downward and nesting said successive stacks within said trough, a plurality of retaining fingers normally overlying the sides of said trough for retaining said nested stacks in engagement with the sides of said trough, means for removing said retaining fingers from said trough while each stack is transferred thereto, and means for periodically removing a predetermined number of nested stacks from said trough.

10. In a machine of the character described, a rotary paper carrying cylinder, means for carrying a plurality of aligned continuous paper sheets on the surface of said cylinder, means for cutting said sheets into stacks of a predetermined length, means for creasing said stacks at their mid-points, a downwardly tapered trough below said cylinder communicating with the surface thereof, means for successively removing said stacks from said cylinder to said trough with their creased edges downward and nesting said successive stacks within said trough, a plurality of retaining fingers normally overlying the sides of said trough for retaining said nested stacks in engagement with the sides of said trough, means for removing said retaining fingers from said trough while each stack is transferred thereto, and means operated in timed relation to the rotation of said cylinder for periodically opening the lower end of said trough and removing a predetermined number of combined stacks therefrom.

11. In a machine of the character described, a rotary paper carrying cylinder, means for carrying a plurality of aligned

continuous paper sheets on the surface of said cylinder, means for cutting said sheets into stacks of a predetermined length, means for creasing said stacks at their mid-points, a downwardly tapered trough below said cylinder communicating with the surface thereof, means for successively removing said stacks from said cylinder to said trough with their creased edges downward and nesting said successive stacks within said trough, a plurality of retaining fingers normally overlying the sides of said trough for retaining said nested stacks in engagement with the sides of said trough, means for removing said retaining fingers from said trough while each stack is transferred thereto, means for successively opening the lower end of said trough after a predetermined number of paper stacks have been nested therein, and means adjacent the lower end of said trough for withdrawing said predetermined number of paper stacks therefrom in a single folded section.

12. In a machine of the character described, a rotary paper carrying cylinder, means for carrying a plurality of aligned continuous paper sheets on the surface of

said cylinder, means for cutting said sheets into stacks of a predetermined length, means for creasing said stacks at their mid-points, a downwardly tapered trough below said cylinder communicating with the surface thereof, means for successively removing said stacks from said cylinder to said trough with their creased edges downward and nesting said successive stacks within said trough, a plurality of retaining fingers normally overlying the sides of said trough for retaining said nested stacks in engagement with the sides of said trough, means for removing said retaining fingers from said trough while each stack is transferred thereto, means operated in timed relation to the rotation of said cylinder for periodically opening the lower end of said trough after a predetermined number of paper stacks have been nested therein, and a plurality of rollers adjacent the lower end of said trough for withdrawing said predetermined number of paper stacks from said trough in a single folded section.

In testimony whereof I affix my signature.

FELICE MASSA.
